GAME APPARATUS WITH MECHANICAL PROJECTILE PROPELLING MEANS

William H. Fischer, Paramus, N. J.

Application June 8, 1953, Serial No. 360,257

8 Claims. (Cl. 273—126)

This invention relates to a novel mechanical game apparatus constituting a miniature form of an outdoor game and having novel mechanical features enabling a very accurate play of the game thereby making the use of the game apparatus extremely interesting to both adults and children.

More particularly, it is an aim of the present invention to provide a game apparatus which closely simulates the game of shuffle-board and including novel disk impelling means whereby the disks are engaged and retracted with the impelling unit and thereafter projected and released therefrom to slide with a maximum of accuracy over a playing surface toward a scoring area of the surface.

A further object of the invention is to provide a projectile propelling unit constituting a part of the game apparatus and supported by the game board and which may be adjusted laterally and angularly relatively to the game board and an elongated playing surface thereof for accurately propelling the playing disks or pieces along the playing surface from the propelling unit.

Another object of the invention is to provide a propelling unit which is so constructed that it will be accurately retained in any adjusted position while the disk or playing piece is propelled therefrom.

Still a further object of the invention is to provide a propelling unit wherein the force providing means for the unit may be readily adjusted and wherein the force providing means additionally functions as a shock absorbing or cushioning means.

Another object of the invention is to provide a game apparatus including a disk propelling unit having a novel structure for gripping and releasing the disk and accomplishing the propelling thereof over the playing surface.

Various other objects and advantages of the invention will hereinafter become more fully apparent from the following description of the drawings, illustrating a presently preferred embodiment thereof, and wherein:

Figure 1 is a fragmentary top plan view of the game apparatus;

Figure 2 is an enlarged fragmentary longitudinal sectional view thereof taken substantially along a plane as indicated by the line 2—2 of Figure 1;

Figure 3 is a fragmentary bottom plan view on an enlarged scale of the right-hand end of the game apparatus as illustrated in Figure 1;

Figure 4 is a cross sectional view of the game apparatus taken substantially along a plane as indicated by the line 4—4 of Figure 2;

Figure 5 is an enlarged fragmentary cross sectional view taken substantially along a plane as indicated by the line 5—5 of Figure 2, and

Figure 6 is a fragmentary top plan view, partly in horizontal section, of a portion of the right-hand end of the apparatus and showing one of the disks engaged by the propelling unit.

The game apparatus, designated generally 8, includes a game board, designated generally 9, a mechanical disk

2

propelling unit, designated generally 10, and a plurality of disks or playing pieces 11.

The game board structure 9 includes corresponding side walls 12, an end wall 13 which extends between and is suitably secured to corresponding ends of the side walls 12 and an end wall 14 which extends between and is suitably secured to the opposite ends of the side walls 12. The side walls 12 and end walls 13 and 14 are provided with communicating grooves 15 adjacent upper edges thereof in which the side edges and ends of a platform member 16 are disposed for mounting the platform member in the side walls and end walls. It will be readily understood that the side walls and end walls are assembled around the platform member 16. A relatively thin strip of material 17 is suitably secured to the upper surface of the platform 16 and is provided with a smooth preferably highly polished top surface forming a playing surface. Said playing surface or strip 17 is spaced from the side walls 12 and the end wall 13, but extends to the end wall 14, and combines with the side walls 12 and end wall 13 to form alleys 18, the surfaces of which are formed by portions of the platform 16. Said alleys 18 are located between the playing surface 17 and the walls 12 and end wall 13. The playing surface 17 adjacent the end wall 13 is inscribed on its upper side with a scoring area, designated generally 19, including three transverse and longitudinal rows of squares numbered irregularly from "1" to "9." The scoring area 19 also includes two transversely extending wide strips at each end of the rows of squares the inner one of which bears the inscription "10 off" and the outer one of which, located adjacent the end wall 13, bears the numeral "10." The end wall 14 is provided with a large notch 20 which opens outwardly of the bottom edge of said wall and extends to adjacent the side walls 12, as best illustrated in Figures 2, 3 and 4. Cushioning strips or pads 21 are suitably secured to the bottom edges of the side walls 12 and end walls 13 and 14 at the corners of the game board structure 9 and are adapted to rest on any suitable supporting surface such as a table to maintain the remainder of the game board structure 9 out of engagement therewith, to prevent slippage of the game board structure or marring of the table or other surface on which said structure is supported.

The disk or playing piece propelling unit 10 includes a pair of strips 22 and 23 which are secured to the underside of the platform 16 adjacent the ends thereof by suitable fastenings 24 which are anchored in the alley portions 18 of the platform 16. The strips 22 and 23 are longitudinally spaced relatively to one another and extend transversely of the game board 9, the strip 22 being located adjacent to but spaced slightly from the end wall 14 and the strip 23 being spaced a somewhat greater distance from said end wall 14. The portions of the strips 22 and 23 between the fastenings 24 are downwardly offset relatively to the end portions of the strips so as to be spaced from the underside of the platform 16, as best illustrated in Figures 2, 4 and 5. The propelling unit 10 also includes a relatively thin bar 25 having an end portion 26 which is supported by and slidably engages on the upper side of the downwardly offset portion of the strip 22 and an opposite end portion 27 which is supported by and slidably engages on the upper side of the downwardly offset portion of the strip 23. The end portion 27 is of a length substantially greater than the width of the strip 23 and has a downwardly curved terminal portion 28. The bar 25 also includes a downwardly offset intermediate portion 29 which is provided with a longitudinally extending slot 30, and upright portions 31 and 32 connecting the ends of the intermediate portion 29 to the inner ends of the end portions 26 and 27, respectively. The upright bar portions 31 and 32 are spaced

apart a distance less than the spacing between the strips 22 and 23, so that the bar 25 may not only be slid on the strips 22 and 23 laterally of the board structure 9 but so that said bar 25 may also be swung on said strips to different angles relatively to the longitudinal axis of the game board 9. However, the upright bar portions 31 and 32 are disposed sufficiently close to the supporting strips 22 and 23 to prevent the end portion 26 from being disengaged from the strip 22 by a swinging movement of the bar 25, the end portion 27 being additionally prevented from being disengaged from the supporting strip 23 by its downturned terminal 28. The bar portions 31 and 32 are provided with aligned openings 33 to slidably receive a guide rod 34 which extends therethrough and which is slidably supported therein.

An expansion coil spring 35 is coiled around a portion of the guide rod 34 and is disposed between and has its ends bearing against the bar portions 31 and 32. A stop pin 36 extends transversely through a portion of the rod 34 and is anchored therein. The stop pin 36 extends through a convolution of the spring 35 and has one end slidably engaging in the slot 30. The pin 36 is normally disposed nearer the bar portion 32 than the bar portion 31 and a greater number of the convolutions of the spring 35 are disposed between the bar portion 31 and pin 36 than between said pin and the bar portion 32, as clearly illustrated in Figure 2. As seen in Figure 2, a straight end of the guide rod 34 extends forwardly or outwardly from the bar portion 32 a distance at least equal to the length of the slot 30, which limits the length of sliding movement of said guide rod. The other end portion of the guide rod 34 extends outwardly or rearwardly from the bar portion 31 through the notch 20 and has an upwardly offset terminal portion 37 which is disposed above the level of the playing surface 17. Said rod portion 37 is secured in a knob or handle 38, as best illustrated in Figure 6. An upright portion 39 of the guide rod 34, of which the portion 37 forms a continuation, is normally spaced outwardly a substantial distance from the end wall 14.

The propelling unit 10 includes a disk engaging fork 40 comprising two elongated resilient fork shanks 41 having corresponding ends which are suitably secured in a recess 42 of the rod portion 37, and having opposite free ends 43 which are outwardly bowed relatively to one another to provide fork tines which are curved to engage more than halfway around any one of the disks 11. The terminal or distal ends of the fork tines 43 defining the open mouth of the fork are spaced a distance apart less than the spacing of other portions of said tines 43 which are spaced from said distal ends, when the shank portions 41 are disposed in abutting engagement, as illustrated in full lines in Figure 6, so that the fork tines 43 will resiliently and frictionally engage a disk 11 which is disposed therebetween, as illustrated in Figure 6.

In using the game apparatus 8 for the play of a game similar to the game of shuffle board, each of two players ordinarily uses three of the disks 11, six of said disks normally being provided, three of which have a top surface of one color and the other three of which have a top surface of another color to distinguish the playing disks of one player from those of another. However, other means may be provided for distinguishing the two sets of playing disks 11 which otherwise are identical and which are preferably relatively thick as illustrated and formed of a relatively heavy material such as steel. As it will be readily apparent the idea of each player is to propel his disk along the playing surface 17 by means of the propelling unit 10 toward the scoring area 19 and so that the disk will stop on one of the nine numbered squares or the end space bearing the legend "10." A player whose disks stop on these spaces and are not subsequently driven therefrom makes a score for each disk corresponding to the score of the space on which the disk remains at rest. Disks which do not reach the scoring area 19 or slide

from the playing surface 17 into one of the alleys 18 do not make a score while any disk remaining at rest on the space marked "10 off" counts a minus 10 for the player using said disk.

5 Each player in using the game apparatus 8 first slips one of his disks 11 into position between the fork tines 43, as illustrated in Figure 6, said fork tines and the shanks 41 springing apart as illustrated in dotted lines to receive the disk and thereafter springing together so that 10 the disk is gripped by the tines 43. The player can then slide or swing the bar 25 and guide rod 34 relatively to the strips 22 and 23 to angularly and laterally adjust the longitudinal axis of the fork 40 relatively to the longitudinal axis of the playing surface 17. When this adjustment has been accomplished to the satisfaction of the 15 player, the knob 38 is gripped between the thumb and index finger, or otherwise as desired, for retracting the guide rod 34 and fork 40 from left to right of Figures 1 to 20 3 and 6 for compressing the portion of the spring 35 located between the bar portion 31 and pin 36 to the extent desired. The knob 38 is then released allowing said 25 portion of the spring 35 to forcibly propel the guide rod 34 and fork 40 in the opposite direction or from right to left. The spring portion located between the pin 36 and bar portion 32 is released from tension by the previous retraction of the guide rod and fork and as said parts are propelled from right to left by the first mentioned longer portion of the spring, the last mentioned shorter portion, moving with the rod 34, will strike the bar portion 32 30 and not only cushion the sudden stopping motion of the fork and guide rod but will cause said parts to spring backward or from left to right slightly. The inertia of the movement of the disk from right to left with the fork 40 will cause said disk to spread the fork tines 43 and the 35 shanks 41 when the right to left movement of the fork is suddenly stopped as previously described and the disk 11 will continue to slide along the surface 17 toward the scoring area 19 and if accurately propelled by the player will come to rest on one of the favorable scoring spaces, 40 as previously described.

The sliding and pivotal mounting of the bar 25 on the two supporting strips 22 and 23 provides a two point pivot and sliding support which will effectively retain the guide rod 34 and fork 40 in proper position of alignment relatively to the playing surface 17 to which said parts have 45 been previously set by the player, and the setting thereof will not be changed should the release of the knob 38 not be smoothly accomplished, as would readily occur if the bar 25 were pivoted relatively to the game board structure 9 at only one point. The pin 36 will also effectively prevent any turning of the guide rod 34 relatively to the bar 25 so as to maintain the fork 40 above and spaced from the playing surface 17. The spring 35 may be turned relatively to the rod 34 to vary the tension on the 50 longer and shorter end portion thereof disposed on opposite sides of the pin 36 to obtain the most satisfactory result. Such turning of the spring will obviously be relatively to the pin 36 and will vary the number of convolutions of the spring located on each side of the pin 36. As 55 the slot 30 is directly in line with the guide rod 34 and fork 40, the fork is caused to accurately move in alignment with the slot 30 to insure accuracy in projecting the disk 11. As the disks 11 are held in the fork tines 43 while the propelling unit 10 is retracted from left to right, 60 each disk moves with the unit 10 until the instant of its release therefrom so that there is no striking of the disk by the impeller which would tend to cause an inaccurate projection.

Obviously, the rules for playing the game may vary but 65 preferably conform to the rules of play for the conventional game of shuffle board.

Various modifications and changes are contemplated and may obviously be resorted to, without departing from the spirit or scope of the invention as hereinafter defined 70 by the appended claims.

I claim as my invention:

1. A game apparatus comprising an elongated game board structure including a first end and a second end and provided with an elongated upwardly facing playing surface having a scoring area at one end thereof and adjacent the first end of the game board structure, said game board structure including a chamber disposed beneath the playing surface, and a disk projecting unit mounted on the game board structure adjacent the second end thereof, said projecting unit including supporting means mounted in said chamber beneath the playing surface and laterally and angularly adjustable relatively to the game board structure, a guide rod slidably mounted in said supporting means and movable relatively thereto generally in directions longitudinally of the game board structure and movable therewith laterally and angularly of the game board structure, spring means urging the guide rod toward said first end of the game board structure, a disk supported on the playing surface, and a resilient disk engaging fork supported by the guide rod above the playing surface and releasably engaging the disk while the projecting unit is manually retracted away from the first end of the game board structure to load the spring means and for releasing and spring projecting the disk slidably along the playing surface toward the scoring area when the projecting unit is manually released, said supporting means being slidably and turnably supported at two longitudinally spaced points relatively to the game board structure and adjacent ends thereof for maintaining the supporting means in different laterally and angularly adjusted positions while the guide rod and disk engaging fork are manually retracted and spring projected.

2. A game apparatus as in claim 1, said game board structure having alleys including bottoms disposed below the level of said playing surface and extending along side edges of the playing surface and across the end of the playing surface located adjacent said scoring area.

3. A playing piece projecting unit comprising, in combination with an elongated game board having depending supporting means supporting the game board in an elevated position and a playing piece, a guide rod, a guide member having longitudinally spaced portions through which spaced portions of the guide rod slidably extend and in which said guide rod is slidably guided, elongated supporting strips secured to the underside of the game board and transversely thereof, said guide member having end portions slidably and turnably supported on said supporting strips for laterally and angularly adjusting the guide member and guide rod relatively to the game board, said guide rod having an upwardly offset handle portion disposed beyond an end of the game board, a playing piece engaging member having one end secured to said handle portion, said playing piece engaging member being supported by the guide rod and having an opposite end disposed above the game board for movement relatively thereto longitudinally, laterally and angularly in unison with the guide rod, said last mentioned end terminating in a playing piece receiving portion releasably engaging

5

6

the playing piece for propelling the playing piece along a top surface of the game board, and spring means for projecting the guide rod and playing piece engaging member in one direction relatively to said guide member from a retracted position, said guide rod and playing piece engaging member being adapted to be manually retracted by engagement with said handle portion.

4. A playing piece projecting unit as in claim 3, said spring means comprising an expansion coil spring disposed around a portion of the guide rod and having one end bearing against one of said longitudinally spaced guide member portions, a pin anchored in and extending transversely from the guide rod through a convolution of the spring and forming a spring stop whereby the guide rod and playing piece engaging member will be projected from a retracted position by the loaded portion of the spring located between said pin and said aforementioned guide member portion.

5. A playing piece projecting unit as in claim 4, said guide member including an intermediate portion having a longitudinal slot disposed parallel to the axis of the adjacent portion of the guide rod and slidably receiving one end of said pin for slidably and non-turnably retaining the guide rod in said guide member and to insure axial sliding movement of the guide rod relatively to the guide member.

6. A playing piece projecting unit as in claim 5, the other end portion of said spring being disposed between said pin and the other guide member portion to provide a resilient cushioning means and shock absorber for stopping the spring projected movement of the guide rod and playing piece engaging member.

7. A playing piece projecting unit as in claim 3, said playing piece engaging member comprising a fork composed of two resilient shanks having corresponding ends anchored in said handle portion and outwardly bowed opposite free ends forming fork tines releasably engaging the playing piece, said playing piece being of disk-like construction, said fork tines and shanks being spring biased toward one another whereby the fork tines will engage around more than one-half the periphery of the playing piece and being sprung apart for receiving the playing piece therein and for releasing the playing piece therefrom.

8. A playing piece projecting unit as in claim 3, said end portions of the guide member being frictionally engaged between said supporting strips and the game board to retain the guide member in different laterally and angularly adjusted positions.
